[57] CLAIM

The ornamental design for a medical examination light, as shown and described.

DESCRIPTION

FIG. 1 is a perspective view of the medical examination light showing my new design;

FIG. 2 is a top plan view thereof;

FIG. 3 is a front elevational view thereof, the rear elevational view being a mirror image thereof;

FIG. 4 is a bottom plan view thereof;

FIG. 5 is a right side elevational view thereof;

FIG. 6 is a left side elevational view thereof;

FIG. 7 is a perspective view of another embodiment of the invention which differs from the first embodiment only in that the mounting bracket is plain with a horizontal recess; and,

FIG. 8 is a perspective view of still another embodiment of the invention which differs from the first embodiment only in that the mounting bracket is plain.
